US00D785010S

(12) United States Design Patent (10) Patent No.: US D785,010 S
Bachman et al. (45) Date of Patent: * Apr. 25, 2017

(54) DISPLAY SCREEN OR PORTION THEREOF WITH GRAPHICAL USER INTERFACE

(71) Applicant: Apple Inc., Cupertino, CA (US)

(72) Inventors: William Martin Bachman, San Jose, CA (US); Drew Rocky Domm, Oakland, CA (US); Alexander C. D. Fringes, San Francisco, CA (US); Monika E. Gromek, Oakland, CA (US); Joseph Andrew Magnani, San Francisco, CA (US); Ofer Morag, Oakland, CA (US); Jeffrey L. Robbin, Los Altos, CA (US)

(73) Assignee: Apple Inc., Cupertino, CA (US)

() Term: 15 Years

(21) Appl. No.: 29/541,164

(22) Filed: Sep. 30, 2015

(51) LOC (10) Cl. 14-04

(52) U.S. Cl.

USPC D14/485; D14/493

CLAIM

The ornamental design for a display screen or portion thereof with graphical user interface, as shown and described.

DESCRIPTION

FIG. 1 is a front view of a display screen or portion thereof with graphical user interface showing our new design; and, FIG. 2 is a second embodiment thereof.

The peripheral dashed broken lines illustrate a display screen or portion thereof and form no part of the claimed design. The remaining dashed broken lines illustrate text and other features that form no part of the claimed design.

1 Claim, 2 Drawing Sheets
